UNITED STATES PATENT OFFICE.

ELIHU THOMSON, OF SWAMPSCOTT, MASSACHUSETTS, ASSIGNOR TO GENERAL ELECTRIC COMPANY, A CORPORATION OF NEW YORK.

ELECTRIC HEATER.

No. 902,024.

Specification of Letters Patent.

Patented Oct. 27, 1908.

Application filed June 17, 1907. Serial No. 379,352.

To all whom it may concern:

Be it known that I, ELIHU THOMSON, a citizen of the United States, residing at Swampscott, in the county of Essex, State of Massachusetts, have invented certain new and useful Improvements in Electric Heaters, of which the following is a specification.

This invention relates to electric heaters and has for its object the provision of a device of this character whereby the energy of an electric current will be transformed into heat in a safe and efficient manner.

In carrying out my invention I utilize as the medium of distribution of the heat energy, a fluid, such as water, which will be vaporized. Only a small amount of fluid is used however, and the energy is not transformed by circulation of the fluid but by the generation of vapor within a sealed or air-tight receptacle. A limited quantity of fluid is vaporized and then enters an extended space in which the air may be rarefied or not as desired. When the vapor is condensed it returns to the bottom of the vessel where a heating device, such as an electric heating coil, is located. Although it is not essential that the air be exhausted or rarefied in the apparatus, it is essential that the space for the fluid and vapor should be sealed or air-tight so that the quantity of fluid will remain constant. The surface exposed to the air or the condensing surface is calculated to be in excess of that which would be required to dissipate the heat produced by the electric unit at boiling temperature or at a given pressure. In other words, the surface will be such that the temperature will never get beyond the boiling point of the fluid, or it may be so arranged that a slight pressure may be generated within the condensing space, but the pressure will never rise above the predetermined point. The amount of water present at any time will be so small that there will be no danger of injury by freezing or the like. A practically perfect distribution of the radiating surface is thus obtained in a very safe and simple manner.

In the accompanying drawing I have shown my invention embodied in a specific structure which it should be understood is merely for purposes of illustration.

In the drawings, Figure 1 is a side elevation of an electric heater embodying my invention, the casing being partly broken away; Fig. 2 is an end elevation of the same

likewise partly broken away; Fig. 3 is a sectional elevation of a slightly modified form of my invention; Fig. 4 is an end elevation of the same partly in section; and Fig. 5 is a transverse section thereof.

Referring to drawings (Figs. 1 and 2) 10 is a sheet metal corrugated casing entirely inclosed and sealed water-tight. The casing is somewhat contracted in length at the bottom and is provided with an electric heating unit 11 extending longitudinally and centrally of the casing. The unit fits into a sleeve 12 which is preferably supported only at the ends so as to leave an annular space 13 for the fluid 14 which may be water, if desired. The sleeve is united to the casing by a tight joint to prevent the escape of liquid and vapor. By this arrangement the fluid is in heat-conductive relation to the unit, and can quickly be brought up to the boiling 75 temperature. When the water boils, steam will rise into the condensing space 15 and will be condensed and run back into the bottom of the casing. The radiating surface is large enough to condense all of the vapor produced by the heating unit at boiling temperature of the water so that practically no pressure will be generated within the casing. If desired, however, the radiating surface may be so proportioned to the supply of 85 heat that a predetermined pressure may exist in the casing. As the vapor rises it is condensed and almost a perfect distribution of the heat is made throughout the casing. If desired, the air in the casing may be exhausted or rarefied and the apparatus may be worked with the water below its normal boiling point. In this case the water may be vaporized at almost any temperature above the freezing point when the distribution of heat will be perfect and in proportion to the heat energy absorbed by the electric resistance. The small amount of water makes an accident due to excessive pressure or the like impossible.

Figs. 3 to 5 show a similar arrangement, the only difference being the specific construction through which the fluid is heated by the electric unit. In this case a plug of good conducting metal 16 such as copper or the like, forms the bottom of the casing and the heating unit 17 is inserted centrally thereof. The water lies in a shallow groove formed in the upper part of this piece and therefore will be very readily vaporized.

Either of these types is very convenient for small units to be hung on the wall in such places as staterooms on steamships and the like. In Fig. 4 I have shown the heater provided with hooks 18 supporting the heater whereas in Figs. 1 and 2 it is intended to stand upon the legs 19.

It will be understood, of course, that I have, in accordance with the patent statutes, shown and described specific means whereby the invention may be carried out, but it should be further understood that other means will suggest themselves to those skilled in the art without departing from the spirit of my invention, the scope of which is set forth in the annexed claims.

What I claim as new and desire to secure by Letters Patent of the United States, is,—

1. An electric heater comprising an air-tight receptacle containing a quantity of fluid, an electric heating device for vaporizing said fluid, and radiating walls inclosing an extended space communicating with said fluid adapted to condense the vapor, the condensing space being larger than the fluid space.
2. An electric heater comprising an air-tight receptacle containing a quantity of fluid, an electric heating device in heat-conductive relation to said fluid, and radiating walls forming a space communicating with said fluid and arranged to condense the vapor, the condensing space being several times as large as the fluid space.
3. An electric heater comprising an air-tight receptacle having heat radiating walls,

a quantity of fluid in said receptacle and occupying a small portion of the space thereof, and an electric heating device in conductive relation to said fluid arranged to vaporize the same.

4. An electric heater comprising an air-tight receptacle containing a quantity of fluid and having a condensing space several times larger than the fluid space above and in communication with said fluid, and an electric heating device for vaporizing said fluid.

5. An electric heater comprising a fluid container, an electric heating device in heat-conductive relation thereto, and a corrugated casing forming a condensing space communicating with the fluid.

6. An electric heater comprising an air-tight receptacle containing a quantity of fluid, means for vaporizing said fluid, radiating walls forming an extended space communicating with said fluid, said walls having a radiating surface in excess of that required to dissipate the heat produced at substantially the boiling temperature of the fluid.

7. An electric heater comprising a closed container, a vaporizable fluid therein and a heating unit for the fluid, said container having an internal capacity sufficient to contain the completely vaporized fluid at approximately atmosphere pressure.

In witness whereof, I have hereunto set my hand this twelfth day of June, 1907.

ELIHU THOMSON.
